EYE SHIELD

Jack N. Simpson, Reading, and Charles J. Boyer, West Reading, Pa., assignors to The Electric Storage Battery Company, Philadelphia, Pa.

Filed Feb. 6, 1963, Ser. No. 73,464

Term of patent 14 years

(Cl. D57—1)

Fig. 3.

Fig. 1.

Fig. 2.

FIG. 1 is a side perspective view of an eye shield showing our new design;

FIG. 2 is a front view thereof; and

FIG. 3 is a perspective view thereof shown in exploded position.

The side not shown is substantially like the side shown.

The rear of the eye shield not shown conforms substantially in contour to the front portion thereof, as indicated.

We claim:

The ornamental design for an eye shield, substantially as shown and described.
